UNITED STATES PATENT OFFICE.

JOHN C. SCOVEL, JR., OF CHICAGO, ILLINOIS, ASSIGNOR TO CONTINENTAL MACHINE AND FOUNDRY COMPANY, OF WILMINGTON, DELAWARE, A CORPORATION OF DELAWARE.

CONTROL-HEADER FOR REFRIGERATING APPARATUS.

1,247,884.

Specification of Letters Patent. Patented Nov. 27, 1917.

Application filed November 13, 1916. Serial No. 131,065.

To all whom it may concern:

Be it known that I, JOHN C. SCOVEL, Jr., a citizen of the United States, and a resident of Chicago, in the county of Cook and State of Illinois, have invented certain new and useful Improvements in Control-Headers for Refrigerating Apparatus; and I do hereby declare that the following is a full, clear, and exact description thereof, reference being had to the accompanying drawings, and to the letters of reference marked thereon, which form a part of this specification.

This invention relates to an improved central control header for connecting compressors of refrigerating apparatus to the discharge and return lines and consists of the matters hereinafter described and more particularly pointed out in the appended claims.

20 The object of the invention is to provide a central control header of the kind described, which will provide in simple and economical form, both as to manufacture and as to attachment, means for reversing the action of the compressor or pump on the rest of the apparatus, as for example, means for connecting the high pressure side of the apparatus to the low pressure side, when it is desired to clean or repair the apparatus.

25 Another object of the invention is to provide a header of the kind described which has a valve mechanism so constructed that in starting the compressor, the high pressure side may be connected for a short time with the low pressure side, during which time the compressor will operate idly until it has attained full speed and momentum, thus obviating the enormous strain that is ordinarily put upon the motor or engine when 30 the compressor is first started into operation.

In the drawings:

Figure 1 illustrates a view in side elevation of a refrigerator compressor equipped with my improved control header.

45 Fig. 2 illustrates a view in front elevation of the same, the crank case of the compressor being shown in section.

Fig. 3 illustrates on an enlarged scale, a central, vertical sectional view through the 50 control header, the plane of the section being indicated by the line 3-3 of Fig. 2.

Fig. 4 illustrates a horizontal, transverse, sectional view through the control header,

the plane of the section being indicated by the line 4-4 of Fig. 3.

55

Fig. 5 illustrates a horizontal, transverse sectional view through the control header, the plane of the section being indicated by the line 5-5 of Fig. 3.

Fig. 6 is a similar view, the plane of the 60 section being indicated by the line 6-6 of Fig. 3.

Fig. 7 illustrates a detail sectional view through a valve structure employed in my improved header, the plane of the section 65 being indicated by the line 7-7 of Fig. 3.

Referring now in detail to that embodiment of my invention illustrated in the accompanying drawings,—10 indicates a multi-cylinder compressor of any usual type 70 suitable for use in connection with a refrigerating apparatus. As illustrated herein, the compressor is of the two cylinder, upright type. 12 indicates the upright, hollow base and crank case of the compressor; 13, 75 13 indicate the cylinders; 14, 14, the pistons which reciprocate therein; 15, 15 the crank pins; 16, the crank shaft mounted in the upright side walls of the crank case; and 17 indicates a balance pulley fixed to one end 80 of the crank shaft for driving it.

18 indicates the central control header which is connected to the front side of the two cylinders. The header 18 is a multiple valve casing which may be cast in the form 85 of a single, substantially, rectangular block. In said block are provided chambers 20 and 21 separated by means of a partition wall 22. A valve chamber 23, provided in the upper end of the block, is connected by a 90 pipe 24 to the condenser of the apparatus (not shown). A ported valve seat 25 is interposed between the chamber 20 and the valve chamber 23. A valve chamber 26 is formed in the bottom end of the block below 95 the chamber 21 from which it is separated by means of a ported valve seat 27. The chamber 20 is connected by pipe fittings 28, 28 to the discharge or outlet ports of the several cylinders. The valve chamber 26 is 100 connected by pipe fittings 28, 28^a to the several suction or inlet ports of the compressor. Said fittings 28, 28 and 28^a, 28^a, as shown, extend from the sides of the block or casting, which is preferably placed symmetrically 105 between the two cylinders of the com-

Fig. 3 illustrates on an enlarged scale, a central, vertical sectional view through the 50 control header, the plane of the section being indicated by the line 3-3 of Fig. 2.

Fig. 4 illustrates a horizontal, transverse, sectional view through the control header,

pressor. The chamber 21 is connected by a pipe 24^a to the expansion coil.

At one side of the valve chamber 23 is formed a ported valve seat 29 for connecting a valve chamber 29^a and a by-pass 30 connects said valve chamber with the valve chamber 26. The several valve chambers mentioned are closed by means of suitable bonnets attached to the valve casing in any convenient or well-known manner, and are provided with stuffing boxes and glands through which their respective valve stems extend so as to be operable from the outside of the casing.

31 indicates the bonnet, stuffing box and gland of the valve chamber 23. 32 is a hand-valve stem having threaded engagement with said bonnet and operatively connected with a valve 33 which is adapted to be closed on the ported valve seat 25. Said valve comprises two parts, namely, a plug 34 which is screwed upon the reduced end 32^a of the valve stem with a thread the reverse of that part of the stem that is threaded through the bonnet; and a relatively movable tubular valve plug 35 which is adapted to close directly on the valve seat 25. Said tubular plug, as shown, is of greater diameter than the plug 34 and a tubular flange 36 depending from the bonnet 31 provides a bearing between the two plugs. A pin or screw 37 fixed to the plug 34 and engaged in a slot 37^a in the flange 36 (extending parallel to the valve stem 32) prevents rotation of the plug 34 with its stem.

38 indicates the bonnet, stuffing box and gland of the valve chamber 26. 39 indicates a hand-valve stem having threaded engagement with the bonnet and 40 indicates a valve plug adapted to be closed upon the valve seat 27, by means of its engagement with the reduced end 39^a of its stem 39, the reduced end being threaded the reverse of the threaded engagement of the stem in its bonnet. A pin 41 fixed in the bonnet and engaged in a groove 41^a in the valve plug 40 prevents rotation of the plug with the valve stem. 42 indicates the bonnet of the valve chamber 29^a and 43 and 44 indicate respectively the valve stem and valve plug connected therewith. These are of the same construction as those last described.

In the partition wall 22 is provided a ported valve seat 22^a, placed on the side next the chamber 21 and the casing is formed with an opening in line with said valve seat and closed by a bonnet 45. Said bonnet has a tubular valve bore 46 in which a tubular valve plug 47 has reciprocable bearing. Said valve plug is normally closed on the valve seat 22^a and is held closed by means of an expansion coiled spring 47^a having one end seated within it. The other end of said spring seats against a shoulder on a

hand-valve stem 48 which has threaded engagement within a sleeve 49 which in turn is threaded into the bonnet 45. 48^a indicates the threaded part of the stem 48. Said part is of greater diameter than the stem, and is adapted to be limited in its inward movement in the sleeve 49 by means of an internal shoulder 49^a at the base of said sleeve. Manifestly the stem 48 may be operated to adjust the tension of the spring 47^a. The sleeve 49 determines, by its position, the limit of the inward movement of the stem 48, and therefore limits the tension that may be applied to the spring 47^a by the adjustment of the stem 48. This tension is made such that the greatest pressure of the valve against its seat is normally some predetermined amount in excess of the condenser pressure.

The sleeve 49 is closed at its outer end by means of a stuffing box and gland 50 through which the valve stem 48 extends. A fixed ring 48^b surrounding the valve stem and abutting against the stuffing box provides a seat for the large screw-threaded part of the valve stem, which acts as a closure and prevents any tendency to discharge through the stuffing box, when the stem 48 is withdrawn to its outer limit. The sleeve 49 is connected, as shown in the drawings, 95 by a link and seal 49^c to the bonnet 45, so that the tension of the spring 47^a can not be increased without breaking the said seal.

A valve 51 of familiar construction, connected with the chamber 26, which is the low pressure chamber of the casing, is connected by a pipe 52 (see Fig. 1), with a pressure-indicating gage 53. A similar valve 54 is connected with the valve chamber 23 in the high pressure end of the casing, and is likewise connected to a pressure gage (not shown).

As before stated, the pipe 24^a leading from the expansion coil, discharges into the low pressure chamber 21, and to catch and hold such scale or other foreign substance such as is drawn or discharged into said chamber, a scale trap is provided in said chamber. This scale trap comprises a cage 55, having a cylindrical wall of wire mesh 56, said cage being threaded into said casing 18, in line with the pipe 24. The end of said cage without the casing is closed by a squared head 57 and the other end of said cage is open so that the pipe 24^a will discharge into the interior of said cage. It is thus apparent that any scale or other foreign substance discharged from the pipe 24^a will be caught in said cage and prevented from being drawn into the compressor. The construction of the cage is such that it may be easily removed from the casing and cleaned, after which it may be as easily replaced.

The operation of the device is as follows:

The valves are adjusted as illustrated in the drawings when the compressor is running. Prior to starting the compressor, the stem 48 is adjusted to reduce the pressure of the spring 47^a on the check valve 47 to a point below condenser pressure. The compressed fluid discharged into the chamber 20, seeking a way out, will take the path of least resistance, and acting upon the valve 47 and against the pressure of the spring 47^a, will pass into the chamber 21, thence through the valve chamber 26 and the pipes 28^a to the low pressure side of the cylinders. The fluid is thus short circuited from the high pressure side of the cylinders to the low pressure side. This is allowed to continue until the compressor attains full speed and momentum, when the stem 48 is adjusted to bring the spring 47^a to its normal, predetermined maximum tension. The fluid will then be discharged to the condenser in the usual way.

When in making repairs, in cleaning out the scale, or for other reasons, it is desired to reverse the operation of the compressor, so to connect the condenser with the low pressure side of the cylinders and to connect the expansion coil or chamber with the high pressure side of the cylinders, it is necessary to open the valve 44, close the valve 40 and close the valve 33 rigidly upon its seat. The tension of the spring 47^a on the valve 47 is also relieved. This will manifestly connect the valve chamber 23 by means of the by-pass 30, with the valve chamber 26 and thus with the low pressure side of the cylinders. The pressure in the chamber 20 will open the check valve 47 and thus connect the chambers 20, 21 and in that way connect the high pressure side of the cylinders with the expansion coils or chamber of the system.

It will be apparent that the check valve 47 acts as a safety valve and the maximum pressure required to open it may be carefully fixed and determined by the adjustment of the sleeve 49. After the adjustment is made, the link and seal 49^x are attached as heretofore described, and the valve cannot be adjusted to withstand a greater pressure without breaking said seal.

I claim as my invention:

1. A central control header of the kind described comprising a casing having oppositely disposed valve chambers at its ends, and two intermediate chambers, a high pressure chamber and a low pressure chamber, separated by a partition wall, said wall having a ported valve seat on the low pressure side, the high pressure chamber being connected by a port to one of said valve chambers and the low pressure chamber being connected by a port to the second valve chamber, said casing having a third valve chamber opening into the first named valve chamber and having a by-pass connecting

said third valve chamber with said second valve chamber, a combination hand and pressure controlled check valve for closing the port between said first named valve chamber and the said high pressure chamber, a hand controlled valve for closing the port between said third named valve chamber and said first named valve chamber, a hand controlled valve for closing the port between said second named valve chamber and said low pressure valve chamber and a combination hand and spring controlled check valve normally closing the port between said high pressure chamber and said low pressure chamber.

2. A central control header of the kind described comprising a casing having oppositely disposed valve chambers at its ends, and two intermediate chambers, a high pressure chamber and a low pressure chamber, separated by a partition wall, said wall having a ported valve seat on the low pressure side, the high pressure chamber being connected by a port to one of said valve chambers and the low pressure chamber being connected by a port to the second valve chamber, said casing having a third valve chamber opening into the first named valve chamber and having a by-pass connecting said third valve chamber with said second valve chamber, a combination hand and pressure controlled check valve for closing the port between said first named valve chamber and the said high pressure chamber, a hand controlled valve for closing the port between said third named valve chamber and said first named valve chamber, a hand controlled valve for closing the port between said second named valve chamber and said low pressure valve chamber, a spring controlled check valve normally closing the port between said high pressure chamber and said low pressure chamber, and means for predetermined the maximum pressure that said valve will withstand.

3. A central control header of the kind described comprising a casing having oppositely disposed valve chambers at its ends, and two intermediate chambers, a high pressure chamber and a low pressure chamber, separated by a partition wall, said wall having a ported valve seat on the low pressure side, the high pressure chamber being connected by a port to one of said valve chambers and the low pressure chamber being connected by a port to the second valve chamber, said casing having a third valve chamber opening into the first named valve chamber and having a by-pass connecting said third valve chamber with said second valve chamber, a combination hand and pressure controlled check valve for closing the port between said first named valve chamber and the said high pressure chamber, a hand controlled valve for closing the 130

port between said third named valve chamber and said first named valve chamber, a hand controlled valve for closing the port between said second named valve chamber and said low pressure valve chamber, a spring controlled check valve normally closing the port between said high pressure chamber and said low pressure chamber, and means including a locking seal for predetermining the maximum pressure that said valve will withstand.

4. A valve block for a device of the kind described, comprising a casing having a valve chamber in each end and two pressure chambers between said valve chambers, said pressure chambers being separated by a partition wall having a ported valve seat on one

side, each of said pressure chambers being connected by a port to one of said valve chambers in the ends of said casing, said casing also having a third valve chamber opening into one of the first mentioned valve chambers, and having a by-pass connecting said third member with the other one of said first mentioned valve chambers. 25

In testimony, that I, claim the foregoing as my invention I affix my signature in the presence of two witnesses, this 6th day of November A. D. 1916.
